UNITED STATES PATENT OFFICE.

ISAAC C. SHULER, OF AMSTERDAM, NEW YORK.

COFFIN.

SPECIFICATION forming part of Letters Patent No. 330,432, dated November 17, 1885.

Application filed September 12, 1885. Serial No. 176,872. (No model.)

To all whom it may concern:

Be it known that I, ISAAC C. SHULER, a citizen of the United States, residing at Amsterdam, in the county of Montgomery and State of New York, have invented certain new and useful Improvements in Preserving-Cases for Coffins and Caskets, of which the following is a specification.

My invention relates to certain improvements in cases for preserving coffins or burial-caskets; and it consists of the devices and combinations of devices and elements hereinafter particularly described, and specifically set forth in the claim.

15 The object of my invention is to provide a sectional case made of vitreous material in which the parts will be cheaply produced and be readily united and sealed by cement in a water and air tight manner, as will be herein-
20 after described. I attain this object by the means illustrated in the accompanying drawings, forming a part of this specification, in which—

25 Figure 1 represents a horizontal view from above of the case in its parts when joined together. Fig. 2 is a sectional elevation of the same. Fig. 3 is an end view. Fig. 4 is a perspective view of the end closing-pieces, and Figs. 5 and 6 are detailed sectional views of 30 the closing-rings and the ring-sections, respectively.

The same letters of reference refer to like parts throughout the several views.

In the drawings, A represents the case, 35 which is composed of a series of cylinders, *a a*, and a series of detachable and adjustable annular rings, *b b b*, and end closing-pieces, *A' A'*. All of said parts *a*, *b*, and *A'* are made of vitreous material, such as earthenware, 40 stoneware or iron-stone, or other similar material. The cylinders *a a* have made with each end the angular incline *z*. These inclines are about equal, and when said cylinders are joined together with one end neighboring the end of 45 an adjoining cylinder there will be produced an annular V-shaped groove or recess, which will be adapted to receive cement *c*, as shown in Fig. 2. The inner diameter of rings *b*, or their openings, are made to so correspond with 50 the outer diameter of cylinders *a* that they will nicely fit on the latter and be movable on the same in either direction. Made with one end

of each of the cylinders *a* is the internal circular flange, *e*, which projects out past the end to a distance of about one inch, more or less. 55 These internal flanges, *e*, are intended to operate as guides with the coacting and conjoined ends of the neighboring cylinder to facilitate their adjustment with one another, while the V-shaped annular grooves produced by inclines *z z* will hold the cement. The end closing-pieces, *A'*, are each made with the form shown in Figs. 2 and 4, and consists each of a solid piece of circumference about equal to the diameter of cylinders *a*, and provided with a 60 flange-rim, *a'*, all around, as shown. The opening of this flange-rim is made with a diameter corresponding with the outer diameter of said cylinders *a*, so that the end of the same will be readily entered into the flange-rim *a'* of said 65 end pieces. In practice I employ a suitable number of these cylinders *a a* as will be required to produce a length of case sufficient to receive the coffin to be preserved, and I employ over each joint between these cylinders 70 one of the rings *b*. 75

B is a foundation for the coffin-case, which foundation is made of brick or stone laid upon the bottom of the sepulcher or excavation. This case is made to inclose the coffin or casket 8c by slipping over the latter each of the series of cylinders *a* one after the other, and then placing on the same the movable rings *b*, with cement *c*, filling the annular V-shaped grooves formed by the inclines *z z* at the ends of the 85 adjoining cylinders, and then shoving said rings and adjusting the same so that they will be uniformly over the cement *c*, as shown in Fig. 2, and inclose the same. Cement *c* is placed on the incline *z* of the ends of the end 9c cylinders of the series, or may be placed all around in the corners of the annular flanges *a'* of the end closing-pieces where the flanges connect with the circular bodies of the same.

After the several parts—the cylinders *a*, 95 rings *b*, and end closing-pieces, *A'*—have been joined and cemented together, as above described, they will be drawn together and held by means of the draw-bolts *C C* and end tie-pieces, *D D*, which latter may be made with 100 any suitable form of construction, so as to be adapted to have bearing against the respective end closing-pieces, *A'*, and receive the ends of the draw-bolts, as shown. This case can be

applied to the coffin after being placed into the sepulcher or excavation, or above ground and be lowered down into the excavation by any suitable mechanism.

- 5 In applying the cement to the V-shaped grooves I fill the grooves when the cylinders are about one-quarter or one-half of an inch apart, and then draw the cylinders together by draw-bolts C, when the cement will be packed 10 within the chamber between the inclines z z and the rings b, and when set this cement will hold with the cylinders and the rings, so that these parts will be held firm and the joints will be made water and air tight. The internal 15 flanges, e, will operate not only to guide the cylinders when being adjusted and placed to-

gether, but will also operate to prevent the cement from being squeezed inwardly and passing to the inner side of the case.

What I claim, and desire to secure by Letters Patent, is—

In a preserving-case for coffins or caskets, the combination, with a series of cylinders, a a, having inclines z z, internal flange, e, cement c, rings b b, and end closing-pieces, A' A', draw-bolts C C, and tie-pieces D D, all substantially as and for the purposes set forth.

ISAAC C. SHULER.
